US00D660449S

(12) **United States Design Patent**
Sevier et al.

(10) **Patent No.:** **US D660,449 S**
(45) **Date of Patent:** **** May 22, 2012**

(54) **THERAPY INSTRUMENT**

- (75) Inventors: **Thomas L. Sevier**, Fishers, IN (US);
Sue A. Stover, Upland, IN (US)
- (73) Assignee: **Performance Dynamics, Inc.**, Muncie,
IN (US)
- (**) Term: **14 Years**
- (21) Appl. No.: **29/387,942**
- (22) Filed: **Mar. 22, 2011**
